RELAXATION CIRCUITS FOR PRODUCING ELECTRICAL IMPULSES AT REGULAR RE- CURRENCE FREQUENCIES

John Mathieson Dodds, Timperley, and Graham
John Scoles, East Sheen, London, England, as-
signors to Metropolitan-Vickers Electrical Com-
pany Limited, London, England, a company of
Great Britain

Application December 18, 1943, Serial No. 514,866
In Great Britain June 26, 1942

Section 1, Public Law 690, August 8, 1946
Patent expires June 26, 1962

4 Claims. (Cl. 250—36)

1

This invention relates to relaxation circuits for producing electrical impulses at regular recurrence frequencies, more particularly, but not exclusively, for the impulsing of the tripping electrodes of the spark gap device forming inter alia the subject of copending United States applications all filed December 18, 1943, Serial No. 514,863, now Patent No. 2,400,456, issued May 14, 1946; Serial No. 514,864, now Patent No. 2,400,457, issued May 14, 1946; Serial No. 514,865, now Patent No. 2,433,755, issued December 30, 1947, the main electrodes of the spark gap being preferably supplied with energy through the circuits diagrammatically illustrated by Figs. 1, 2 and 3 of the drawings of said copending applications, serial Nos. 514,863 and 514,864 respectively, whilst the tripping is effected through a valve having a small inductance in its anode circuits and having its control grid supplied with "positive-going" impulses from the relaxation oscillator, which heretofore has been per se as described, for use in producing stroboscopic illumination, in Proc. I. R. E., November 1939. Said relaxation oscillator comprises basically a valve having between its cathode and the negative terminal of the anode supply, a timing circuit of resistance R and parallel capacity C whereby the control grid bias is varied through the secondary of an impulse transformer the primary of which is appropriately connected between the valve anode and the positive terminal of the anode supply such that the operation of the circuit is as hereinafter described.

Whilst the present invention will be herein-after described mainly as an addition to the relaxation oscillator circuit described in the last sentence of the preceding paragraph it is to be understood that the invention may be applied to other forms of relaxation oscillator, such, for example, as "Thyratron" (a British registered trade-mark) and "flip-flop" circuits.

The present invention comprises the addition to the per se known relaxation oscillator circuit of a rectifier, such as a diode, in series with an inductance, the latter combination resonating with a condenser at one-half the required recurrence frequency and being connected, such as in the several ways herein-after described, effectively in series with the relaxation oscillator circuit so that the rectifier by the prevention of current reversal causes a very rapid change of potential, as will be herein-after explained, whereby more accurate timing between successive pulses is obtainable than with the known arrangements of relaxation circuits.

To enable the invention to be fully understood

2

it will now be described with reference to the accompanying drawings, Figure 1 of which is a circuit diagram of the known form of relaxation oscillator published in Proc. I. R. E., November 1939, and Figure 2 is a group of graphs indicating various wave forms of electrical quantities operating in the circuit shown in Figure 1;

Figure 3 is a diagram of one circuit arrangement in accordance with the invention, and Figure 4 is a group of graphs indicating the wave forms of electrical quantities which obtain during the operation of the circuits shown in Figure 3;

Figure 5 is a circuit diagram of a modification 15 of the arrangement shown in Figure 3, and Figure 6 is a group of graphs indicating the wave forms of potentials at certain points indicated on the circuit of Figure 5;

Figure 7 is a diagram of a further modification 20 of the circuit, still employing the relaxation oscillator per se generally as shown in Figure 1, and Figure 8 is a group of graphs similar to those shown in Figure 6, but relative to the circuit of Figure 7, and

25 Figure 9 is a circuit diagram showing the invention applied to a "Thyratron" relaxation oscillator.

Referring first to the known arrangement illustrated in Figure 1, the triode or other suitable 30 hard valve V has between its cathode and the negative terminal of the high tension supply, the timing circuit comprising the resistance R and parallel capacity C whereby the control grid bias is varied through the secondary S of the impulse 35 transformer the primary P of which is appropriately connected between the anode of the valve V and the positive terminal of the anode supply, the anode thus having an inductive load L_P as indicated in dotted lines. The operation 40 of the circuit shown in Figure 1 is as follows:

Assume that the condenser C has been charged during the preceding cycle such that the grid-cathode potential biases the valve V beyond the cut-off point. In this condition no current can 45 pass through the valve and no voltage can be developed across the primary or secondary winding of the transformer, so that the anode voltage on the valve is that of the high tension positive supply. The charge on the condenser C leaks away through the resistance R until the 50 impedance of the valve between anode and cathode is no longer infinite, due to the grid bias passing the cut-off point, at the instant of which the grid is still negative to the cathode so that no current can flow in the secondary winding of the

transformer, and hence no current can flow in the primary winding thereof, the instantaneous impedance of the primary being very great. The immediate result is a drop in the potential of the valve anode, resulting in, by the appropriate connection of the transformer windings, a further rise in the potential of the grid relative to the cathode. The transformer ratio may be unity. The rise in grid voltage soon passes the point at which grid current commences to flow, thus permitting an anode current of the same magnitude also to flow. The process continues until the anode voltage becomes too low to maintain the relationship of anode and grid currents as enforced by transformer action. At this point the sense of the transformer voltages will reverse, thus cutting off grid and anode currents almost instantaneously. And since the sum of the grid and anode currents will have been charging the condenser C during this period, the system immediately returns to its initial (cut-off) condition. At the same time the sudden cessation of current through the primary inductance L_p of the transformer causes the energy stored in it during the conducting part of the cycle to reappear as a violent overswing, this voltage also appearing, of course, on the secondary winding of the transformer, in the reverse sense, and causing the valve current to be cut off very suddenly.

In the uppermost graph of Figure 2 the part ab represents the charge of the condenser C leaking away through the resistance R, namely until the impedance of the valve between anode and cathode is no longer infinite, the part bc of the curve indicates the conducting period during which the condenser is charged by the sum of the grid and anode currents of the valve. Thereafter the charge leaks away as indicated by the part cd of the curve. Thereafter the cycle is repeated. The middle graph of Figure 2 indicates (on a different time scale) the wave form of one cycle of the anode voltage, starting from the point of time b in the uppermost curve, whilst the two curves in the lowermost graph of Figure 2 indicate (on this same time scale) the wave forms of both the grid and cathode voltages during the same cycle commencing at the same point of time.

The known relaxation oscillator above described is satisfactory in so far as it produces impulses sufficient to operate the aforesaid spark gap, but the timing circuit RC may not give under some conditions sufficiently accurate timing between successive pulses, a defect which may be accentuated in the presence of strong fields. An object of the present invention is a modification of the above described relaxation oscillator whereby very accurate spacing of the pulses can be obtained such as is required when the aforesaid spark gap is used in connection with radiolocation of the pulse modulation type.

Referring to the arrangement according to the present invention shown in Figure 3, the upper part of the diagram may be considered as identical with that shown in Figure 1, and in the arrangement shown in Figure 3 there is added to the lower end of the resistance R the anode of diode D, the cathode of which is connected through the inductance L_R to the negative terminal of the high tension supply. A condenser C_R is connected across the diode D and inductance L_R , as shown. The values of L_R and C_R are so chosen that the natural frequency of the resonant circuit they form is half that of the recurrent frequency of the pulses to be produced by the

oscillator. Whereas in the arrangement shown in Figure 1 the voltage impulses which may be applied to the valve, which in turn generates impulses for the trigger electrode of the spark gap, are taken from the terminal Q, this is inconvenient in the arrangement shown in Figure 3 on account of the locking wave form so that a tertiary winding T on the transformer is provided.

With regard to the arrangement shown in Figure 3 the part of the circuit comprising V, P, S, R and C operates as described with reference to Figures 1 and 3, so that the condensers C and C_R become charged in series and their separate wave forms are indicated in the uppermost graph of Figure 4. After the pulse the condenser C discharges through the resistance R as previously whilst the condenser C_R discharges through the rectifier D and inductance L_R as shown by the curve jgm . The corresponding current wave form jkl is similar to that of an ordinary resonant circuit except that due to the presence of the diode D current reversal is impossible. Thus the voltage at the junction of the diode cathode and the inductance L_R collapses rapidly to zero at this moment, as shown by the line ml , this change in potential being applied to the grid of the valve V through the winding S. If the value of the resistance R is correctly chosen the valve conducts once more and the cycle repeats. In this way the period between successive impulses is accurately determined over a wide range of the setting of the value of the resistance R.

It is to be appreciated that the graphs in Figure 4 do not show the wave forms when the circuit is "in lock" with L_R and C_R since under these conditions the point h is almost exactly coincident with the point m , which would make the graph difficult to follow. It will be appreciated, furthermore, that the current wave form jkl would be sinusoidal, except that, due to the presence of the diode, the current reversal is prevented and the voltage on the grid of the valve V collapses very rapidly to zero, thus raising in a positive sense the voltage of the grid of this valve with respect to its cathode, as aforesaid.

Referring next to Figure 5 of the drawings, the arrangement therein illustrated differs only from that shown in Figure 3 in that the diode D and its series inductance L_R are connected between the high tension positive supply and the primary winding P of the impulse transformer, the cathode of the diode D being connected through a condenser C_c in series with a resistance R_c to the grid of the valve V. The additional condenser C_R is connected between the inductance L_R and the negative terminal of the high tension supply.

In Figure 6 the graph V_c shows the wave form of the voltage on the cathode of the valve V, the graph L_R the voltage at the "lower" end of the inductance L_R and the graph D_c the voltage of the cathode of the diode D.

The third arrangement shown in Figure 7 differs only from that shown in Figure 5 in the that diode D and inductance L_R are separated and connected in the manner clearly shown in the figure: the additional condenser C_R is connected between the "lower" end of the inductance L_R and the anode of the diode: C_c and R_c are omitted. In this case collapse of the voltage across the inductance L_R imparts a negative impulse to the cathode of valve V. This is, of course, equivalent to applying a positive impulse to the control grid.

In Figure 8 the graph Dc represents the voltage wave form of the cathode of the valve V, the graph L_{R'} shows the wave form of the "lower" end of the inductance L_R, whilst the graph D_a represents the wave form of the anode of the diode D.

Finally in the arrangement shown in Figure 9 the anode of the "Thyratron" V_r is connected through the optional anode inductance L_{F'}, and resistance r to the H. T. + supply, a condenser C' being connected between the junction of inductance L_{F'} and r and H. T.-. The cathode of the "Thyratron," as before, has connected to it the variable resistance R in parallel with the condenser C, and the "lower" end of this circuit is connected to the negative high tension terminal through the diode D and series inductance L_R, the cathode of the diode being connected through a resistance R_g to the grid of the "Thyratron" V_T.

We claim:

1. A relaxation circuit for producing electric impulses at regular recurrence frequencies, comprising a relaxation oscillator including an electric discharge tube having an anode, cathode and control grid, positive and negative supply lines for said anode and cathode respectively, a resonant circuit having a resonant frequency half the recurrent frequency comprising an inductance and condenser in parallel connected between the cathode of said discharge tube and the negative supply line, a diode in the inductive branch of said resonant circuit and connected in the same sense as said discharge tube, and means including a connection between the positive end of said inductance and the grid of said discharge tube whereby said diode prevents reversal of current in the inductance and a positive potential is thereby applied to said grid to initiate an impulse.

2. A relaxation circuit for producing electrical impulses at regular recurrence frequencies, comprising a relaxation oscillator including an inductance effectively connected in circuit therewith, and means including a rectifier and a condenser with which said rectifier and inductance resonate at one-half the frequency of said relax-

ation oscillator for preventing current reversal in the inductance and thereby causing rapid change of potential at the input of said oscillator to initiate an impulse.

3. A relaxation circuit for producing electrical impulses at regular recurrence frequencies, comprising a relaxation oscillator including an inductance effectively connected in circuit therewith, and means including a diode and a condenser connected across said diode and with which said diode and inductance resonate at one-half the frequency of said relaxation oscillator for preventing current reversal in the inductance and thereby causing rapid change of potential at the input of said oscillator to initiate an impulse.

4. A relaxation circuit for producing electrical impulses at regular recurrence frequencies, comprising a relaxation oscillator including an inductance effectively connected in circuit therewith, and means including a diode and a condenser connected to said inductance to form a resonant circuit resonating at one-half the frequency of said relaxation oscillator for preventing current reversal in the inductance and thereby causing rapid change of potential at the input of said oscillator to initiate an impulse.
